UNITED STATES PATENT OFFICE

168,062

AWNNG

Max E. Moore, Houston, Tex.

Application September 23, 1950, Serial No. 12,307

Term of patent 7 years

(Cl. D21—6)

To all whom it may concern:

Be it known that I, Max E. Moore, a citizen of the United States, residing at Houston, in the county of Harris, State of Texas, have invented a new, original, and ornamental Design for an Awning, of which the following is a specification, reference being had to the accompanying drawings, forming a part hereof.

Fig. 1 is a bottom perspective view of an awning, showing my new design;

Fig. 2 is a top perspective view thereof;

Fig. 3 is a front elevational view thereof;

Fig. 4 is a side elevational view thereof; and

Fig. 5 is a cross-sectional view thereof, taken on line 5—5 of Fig. 2, and partly broken away for convenience of illustration.

I claim:

The ornamental design for an awning, substantially as shown and described.

MAX E. MOORE.
